UNITED STATES PATENT OFFICE

GEORGE WALTER SUSSAMS, OF HATFIELD PARK, ENGLAND

DESIGN FOR A GOLF-CLUB HEAD

Application filed September 12, 1930. Serial No. 36,954. Term of patent 7 years, and in Great Britain May 20, 1930.

To all whom it may concern:

Be it known that I, GEORGE WALTER SUSSAMS, a subject of the King of Great Britain, residing at Hatfield Park, Hatfield, Hertfordshire, England, have invented a new, original, and ornamental Design for a Golf-Club Head, of which the following is a specification, reference being had to the accompanying drawing, forming part thereof.

I claim:

The original design for a golf club head, as shown.

GEORGE WALTER SUSSAMS.
